INVENTOR:

William J. Fox

BY *A. V. Jones*
ATTORNEY

UNITED STATES PATENT OFFICE.

WILLIAM J. FOX, OF PHILADELPHIA, PENNSYLVANIA, ASSIGNOR TO JAMES R. KENDRICK CO., INC., OF PHILADELPHIA, PENNSYLVANIA, A CORPORATION OF PENNSYLVANIA.

FABRIC.

Application filed December 24, 1923. Serial No. 682,421.

To all whom it may concern:

Be it known that I, WILLIAM J. FOX, a citizen of the United States, residing at Philadelphia, in the county of Philadelphia and State of Pennsylvania, have invented 5 certain new and useful Improvements in Fabrics, of which the following is a specification.

This invention relates to improvements in 10 knitted fabric having two interconnected webs which are composed of wales or chains of loops and which form the two opposite faces of the fabric; and the invention relates more particularly to such fabric which includes in its construction filling strands 15 which are retained in place within the fabric by and between the webs thereof and the threads connecting the same.

The object of the invention is to relate the 20 threads of the several courses thereof forming the interconnected webs in a novel manner to produce a new fabric having an open or porous mesh, and to produce a new fabric in which the loops of the chains thereof 25 forming the wales will be so relatively proportioned and disposed as to present a novel and attractive appearance either with or without the employment of the filling strands.

With the foregoing and related objects in 30 view, my improved fabric consists of the elements thereof and the combinations of them hereinafter described and claimed.

In the accompanying drawings, illustrating the invention,

Figure 1 is a view of my improved fabric, looking at the forward face thereof.

Figure 2 is a view of the fabric looking at the opposite or reverse face thereof.

Figure 3 is a top view of the fabric, as shown in Fig. 1, with the uppermost filling strand *c* removed therefrom.

Figure 4 is a view similar to Fig. 3 with the uppermost knitted thread *b* removed.

Figure 5 is a top view of Fig. 1 with the uppermost and next adjacent filling strands *c* and the uppermost pair of knitted threads *a* and *b* removed.

Figure 6 is a view similar to Fig. 5 with the uppermost knitted thread *b* shown in Fig. 5 removed.

Referring to the drawings, the fabric comprises knitted threads *a* and *b* and filling strands *c*. The knitted threads are knitted 55 into the fabric individually in succeeding

courses and they are associated together in succeeding pairs, the letters *a* and *b* designating the two threads of each succeeding pair. The filling strands *c* are confined within the fabric by the knitted threads *a* and *b* which act as binding threads therefor.

In the drawings, I have shown four pairs of knitted threads *a* and *b* and numbered them individually 1 to 8, inclusive, in the order in which they are knitted into the fabric from the bottom upwardly so that the course of each individual knitted thread may be followed in the several views of the drawings.

The knitted threads *a* and *b* form wales or chains of loops A, B and A, and C, D and C on the forward and reverse faces, respectively, of the fabric, and they extend from face to face of the fabric between the chains of loops and beneath or between adjacent filling strands *c* and thereby form webs on the respective faces of the fabric between which the filling threads are confined.

Reading from left to right in Figs. 1, 3 and 4 and from right to left in Fig. 2, each thread *a* of the alternate pairs composed of the threads numbered 3, 4 and 7, 8 passes from within the fabric to the forward face of the same and forms a loop in the first chain A, thence back through the fabric to the reverse face thereof and forms a loop in the chain C back of the first chain A, thence forwardly through the fabric, to the forward face thereof and forms a loop in the chain B, thence back again through the fabric to the reverse face thereof and forms a loop in the chain D and thence forwardly 85 into the body of the fabric, and so on, the course just described is repeated and the thread *a* forms loops in other repeated chains similar to the chains A, C, B and D, 90 throughout the fabric; and each thread *b* of the same alternate pairs numbered 3, 4 and 7, 8 passes along the forward face of the fabric and into the first forward chain A and forms a loop therein, thence back through 95 the fabric to the reverse face thereof and forms a loop in the chain C back of the first chain A, thence forwardly through the fabric to the forward face thereof and forms a loop in the chain B, and thence along the 100 forward face of the fabric toward the next adjacent chain A, and so on, the course just described is repeated and the thread *b* forms loops in other repeated chains similar to the chains A, C and B throughout the fabric.

The two threads *a* and *b* of each pair in passing from the forward to the reverse faces of the fabric and back again always pass beneath the same filling strand *c* or between the same two adjacent filling strands *c*.

I shall now describe the courses of the threads of the intervening pairs composed of the threads of the pairs 1, 2 and 5, 6 reading from left to right in Figs. 1, 5 and 10 6 and from right to left in Fig. 2. Each thread *a* of these intervening pairs passes from within the fabric to the reverse face of the same and forms a loop in the first chain *C*, thence forwardly through the 15 fabric to the forward face thereof and forms a loop in the chain *A* in front of the first chain *C*, thence back through the fabric to the reverse face thereof and forms a loop in the chain *D*, thence forwardly again 20 through the fabric to the forward face thereof and forms a loop in the chain *B* and thence back into the body of the fabric, and so on, the course just described is repeated and the thread *a* forms loops in other 25 repeated chains similar to the chains *C*, *A*, *D* and *B*, throughout the fabric; and each thread *b* of the said intervening pairs numbered 1, 2 and 5, 6 passes from within the 30 fabric to the reverse face thereof and forms a loop in the first chain *C*, thence forwardly through the fabric to the forward face thereof and forms a loop in the chain *A* in front of the first chain *C*, thence along the forward face of the fabric to the chain *B* 35 and forms a loop therein, and thence back into the body of the fabric, and so on, the course just described is repeated and the thread *b* forms loops in other repeated chains similar to the chains *C*, *A* and *B*, 40 throughout the fabric.

It will now be understood that the filling strands *c* are not only confined between the webs of the respective faces of the fabric but are also held in separated relationship 45 by the knitted threads *a* and *b* of the several pairs thereof where they pass through the fabric between the filling strands *c*.

It will be observed that each knitted thread *a* forms short loops in the chains *A*, 50 *B* and *C* and relatively longer loops in the chains *D*, and that the chains or wales *D* are formed entirely by the threads *a*. It will also be observed that the chains or wales *A*, *B* and *D* are formed of loops of 55 threads *a* and *b* in alternate succession and that the threads *b* pass directly along the forward face of the fabric between the chains or wales *A* and *B* at certain regularly recurring intervals, as clearly shown 60 in the drawings. These are characteristic features of my invention.

The filling strands *c* may be covered rubber strands or other suitable longitudinally elastic material; and when such material is 65 used the manner of interknitting the threads

a and *b* provides a fabric which will be freely stretchable longitudinally of the filling strands. Such elastic fabrics are used extensively in the manufacture of abdominal supporters, corsets and various other 70 surgical appliances and articles of wearing apparel.

I claim as my invention:—

1. A fabric comprising successive courses of pairs of interknitted threads having 75 chains of loops on the opposite faces of the fabric, each thread of each of certain pairs crossing the body of the fabric from face to face thereof and forming loops in the chains on each face of the fabric, and one 80 thread of each of certain pairs extending between two adjacent loops formed by it in two next adjacent chains on the same face of the fabric at certain intervals.

2. A fabric comprising successive courses 85 of pairs of interknitted threads having chains of loops on the opposite faces of the fabric, one thread of each of certain pairs forming loops in the chains on one face of the fabric and forming relatively short and 90 long loops in the chains on the opposite face of the fabric, the said short loops embracing loops formed by the other thread of the same pair, and said long loops embracing loops formed by a thread of the 95 next adjacent pair.

3. A fabric comprising successive courses of pairs of interknitted threads having 100 chains of loops on the opposite faces of the fabric, one thread of each of certain pairs forming loops in the chains on the respective faces of the fabric in alternate succession, and the other thread thereof forming two loops in the chains on one face of the fabric and one loop in the chains on the 105 opposite face of the fabric in alternate succession.

4. A fabric comprising successive courses of pairs of interknitted threads having 110 chains of loops on the opposite faces of the fabric, one thread of each of certain pairs forming two loops in the chains on one face of the fabric and one loop in the chains on the opposite face of the fabric in alternate 115 succession, the other thread thereof forming loops in the chains on one face of the fabric and forming relatively short and long loops in the chains on the opposite face of the fabric, the said short loops of each of said certain pairs embracing loops formed by the other thread of the same pair, and said long loops of each of said certain pairs embracing loops formed by a thread of the next adjacent pair.

5. A fabric comprising successive courses of pairs of interknitted threads having chains of loops on the opposite faces of the fabric, each thread of each of certain pairs crossing the body of the fabric from face to face thereof and forming loops in the 130

- chains on each face of the fabric, certain loops formed by each thread of each of said certain pairs of the threads embracing certain loops formed by the other thread of the 5 same pair and certain other loops formed by each thread of each of said certain pairs of threads embracing certain loops formed by the threads of the next adjacent pair.
6. A fabric comprising successive courses 10 of pairs of interknitted binding threads having chains of loops on the opposite faces of the fabric, and filling strands extending longitudinally of the courses of binding threads and confined within enclosures 15 formed by and between the pairs of binding threads, each thread of each of certain pairs crossing the body of the fabric from face to face thereof between two adjacent filling strands and forming loops in the 20 chains on each face of the fabric, and one thread of each of certain pairs extending between two adjacent loops formed by it in two next adjacent chains on the same face of the fabric at certain intervals.
- 25 7. A fabric comprising successive courses of pairs of interknitted binding threads having chains of loops on the opposite faces of the fabric, and filling strands extending longitudinally of the courses of binding threads and confined within enclosures 30 formed by and between the pairs of binding threads, one thread of each of certain pairs forming loops in the chains on one face of the fabric and forming relatively 35 short and long loops in the chains on the opposite face of the fabric, the said short loops embracing loops formed by the other thread of the same pair, and said long loops embracing loops formed by a thread of the 40 next adjacent pair.
8. A fabric comprising successive courses of pairs of interknitted binding threads having chains of loops on the opposite faces of the fabric, and filling strands extending 45 longitudinally of the courses of binding threads and confined within enclosures formed by and between the pairs of binding threads, one thread of each of certain pairs forming loops in the chains on each 50 face of the fabric, and the other thread thereof forming two adjacent loops in two next adjacent chains on the same face of the fabric at certain intervals.
- 55 9. A fabric comprising successive courses of pairs of interknitted binding threads having chains of loops on the opposite faces of the fabric, and filling strands extending longitudinally of the courses of binding threads and confined within enclosures formed by and between the pairs of binding threads, one thread of each of certain pairs forming loops in the chains on one face of the fabric and one loop in the chains on the opposite face of the fabric in alternate succession, and the other thread thereof forming two loops in the chains on one face of the fabric and one loop in the chains on the opposite face of the fabric in alternate succession.
10. A fabric comprising successive courses of pairs of interknitted binding threads having chains of loops on the opposite faces of the fabric, and filling strands extending longitudinally of the courses of binding threads and confined within enclosures formed by and between the pairs of binding threads, one thread of each of certain pairs forming two loops in the chains on one face of the fabric and one loop in the chains on the opposite face of the fabric in alternate succession, the other thread thereof forming loops in the chains on one face of the fabric and forming relatively short and long loops in the chains on the opposite face of the fabric, the said short loops of each of said certain pairs embracing loops formed by the other thread of the same pair, and said long loops of each of said certain pairs embracing loops formed by a thread of the next adjacent pair.
11. A fabric comprising successive courses of pairs of interknitted binding threads having chains of loops on the opposite faces of the fabric, and filling strands extending longitudinally of the courses of binding threads and confined within enclosures formed by and between the pairs of binding threads, each thread of each of certain pairs crossing the body of the fabric from face to face thereof between two adjacent filling strands and forming loops in the chains on each face of the fabric, certain loops formed by each thread of each of said certain pairs of threads embracing certain loops formed by the other thread of the same pair and certain other loops formed by each thread of each of said certain pairs of threads embracing certain loops formed by the threads of the next adjacent pair.

In testimony whereof I affix my signature hereto.

WILLIAM J. FOX.
